US0D1072130S

(12) **United States Design Patent** (10) **Patent No.:** **US D1,072,130 S**
(45) **Date of Patent:** **** Apr. 22, 2025**

(54) **PADDLE**

(71) Applicant: **Selkirk Sport, LLC**, Coeur d'Alene, ID (US)

(72) Inventors: **Jacob Blayne Raniere**, Post Falls, ID (US); **Robert James Barnes**, Hayden, ID (US); **Benjamin Michael Hodde**, Spokane Valley, WA (US)

(73) Assignee: **Selkirk Sport, LLC**, Coeur d'Alene, ID (US)

(**) Term: **15 Years**

(21) Appl. No.: **29/911,102**

(22) Filed: **Aug. 29, 2023**

(51) LOC (15) Cl. **21-02**

(52) U.S. Cl.

USPC **D21/731**; D21/698; D21/725; D21/729; D21/799.1; D21/799.2

(57) **CLAIM**

The ornamental design for a paddle, as shown and described.

DESCRIPTION

FIG. 1 is a bottom, front, right-side perspective view of a paddle;

FIG. 2 is a top, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the paddle that form no part of the claimed design. The dot-dashed broken lines represent boundaries of the claimed design and form no part of the claimed design.

1 Claim, 8 Drawing Sheets
